UNITED STATES PATENT OFFICE.

JOHN H. RUEL, OF CHICAGO, ILLINOIS.

FOLDING AND CONVERTIBLE HOLDER FOR BABIES.

1,129,606.

Specification of Letters Patent. Patented Feb. 23, 1915.

Application filed June 19, 1912. Serial No. 774,555.

To all whom it may concern:

Be it known that I, JOHN H. RUEL, a citizen of the United States of America, residing at Chicago, in the county of Cook and State of Illinois, have invented certain new and useful Improvements in Folding and Convertible Holders for Babies, of which the following is a specification.

This invention relates to a seat or holder for infants, and it consists in certain peculiarities of the construction, novel arrangement and operation of the various parts thereof as will be hereinafter more fully set forth and specifically claimed.

The principal object of the invention is to provide a light, portable and inexpensive, yet strong and durable seat or holder for very young babies, the parts of which can be readily folded together, so as to form a compact package, which can be conveniently carried, or if desired, stored away without occupying much room or space.

A further object of the invention is to furnish a seat or holder of the above named general character, the parts of which can be easily and quickly moved or changed from their collapsed or folded positions to their operative or normal ones, to the end, that the device may be used in connection with the back of a common chair to provide a high-chair for the use of babies at the table, or if desired, it can be readily and securely attached to the frame of a "pull-cart" or "sulky," so as to provide a safe and comfortable holder and seat for a child too young to sit and ride on such a vehicle without proper safeguards.

A still further object is to so construct the holder that it can be readily converted into and utilized as a safe seat for swings, or as a baby-holder for "jumpers." Besides, it is adaptable for use as a "pen" to hold a child within certain confines on a sofa, bed or the floor.

Still another object is to provide the holder with an adjustable and detachable tray, which will not only assist in holding the child within the seat or holder, but will afford a support in easy reach for toys, playthings and food.

Various other objects and advantages of the invention will be disclosed in the subjoined description and explanation.

In the accompanying drawings, which serve to illustrate an embodiment of the invention—Figure 1 is a perspective view of

the holder or seat, showing it supported on the back of a common chair to provide a high-chair for a baby, and illustrating by continuous lines normal position of the parts, and by dotted lines the tray in the act of being detached from the supporting arms therefor; Fig. 2 is a side view of the holder, showing it with its parts in their folded positions; Fig. 3 is a greatly enlarged bottom plan view, partly in section, taken on line 3—3 of Fig. 1; Fig. 4 is a side view of the last named figure; Fig. 4^a is a detail view, showing the means for hingedly connecting the back member and seat member at their adjacent edges; Fig. 5 is a fragmental perspective view of a portion of the tray and a part of one of the supporting arms therefor, showing the manner of forming a sleeve at each side of the tray for the reception of the supporting arms; Fig. 5^a is a perspective view, showing the holder mounted on a pull-cart or sulky, and Fig. 6 is a side view of the holder, showing it in use as a holder or seat for a swing or jumper.

Corresponding numerals of reference refer to like parts throughout the different views of the drawings.

The reference numeral 10 designates the back member of the holder and 11 the seat member thereof, which are preferably made of wood, and may be of any suitable size and form in outline. Secured to the side edges of the back 10, are channeled straps or pieces 12, each of which has at its lower end an apertured extension 13, which are preferably extended slightly forwardly as shown in Fig. 4^a of the drawings. Secured to each of the side edges of the seat member 11, is a channeled strap or piece 14, each of which has at its rear end an apertured extension 15, which extensions are preferably projected upwardly as shown in Fig. 4^a of the drawings. The extensions 13 and 15 of the channeled straps 12 and 14 respectively are pivotally connected together by means of pivots 16, extended through the openings in the extensions of said straps, thus hinging the back 10 and seat 11 together, as is apparent. The hinged corners of the back and seat members are preferably covered with felt or other flexible material 17, to prevent marring the chair on which the holder may be supported. Pivotally connected to each of the side edges of the seat 11, near its front end is a link 18, which is pivotally connected at its other end to a link 19, which latter

links are pivotally connected at their upper ends to the side edges of the back 10, near its upper end.

The back 10, has connected thereto at or near each of its upper corners, by means of chains 20, or other flexible connection, hooks 21 to engage the back 22, of a common chair, used to support the holder. These hooks may be suitably covered to prevent them marring the chair on which the holder is mounted. Pivotally connected to each of the links 19, between the ends thereof, is an arm 23, each of which has in its rear end a recess 24, to receive a stud 25, secured to 10 and projecting from each of the channeled members 12, at about the middle thereof. Each of the arms 23, has pivotally connected thereto, near its rear end, a hook catch 26, to engage the studs 25, so as to securely hold the arms 23 in engagement therewith. These arms are slightly flexible or resilient and extend forwardly to a considerable distance beyond the front end of the seat 11, and each has on its outer surface, near its 20 front end, an elongated button 27, to engage a similarly shaped opening 28, formed in each side of the tray 29, near its front portion.

As is clearly shown in Figs. 1 and 4 of the drawings, the openings 28, in the tray, extend longitudinally with respect thereto, while the elongated buttons 27, normally extend transversely with respect to said openings, but it will be understood that by 30 tilting the tray on the pivots provided by the buttons 27, the openings 28 therein may be brought into register with the said buttons, thus allowing them to pass through said openings to permit the tray to be 35 moved. This tray is designated as a whole by the reference numeral 29, and is preferably made of sheet metal, having a dished upper surface; or, in other words, a rim 30, extended around its edges. This rim is 40 preferably formed by up-setting the metal out of which the tray is made, so as to form a channel or groove on the lower surface of the tray. At the rear portion of each of the sides of the tray a recess 31 is formed in 45 the rim 30, for the insertion of the arms 23, which support the tray.

As is clearly shown in Figs. 3 and 5 of the drawings, the downturned or outer portions 32, of the sides of the rim are provided each with an inwardly extended flange 33 to rest beneath the arms 23, but it will be noted that there is considerable space between the inner edge of each of the flanges 33, and the inner wall 34 of each of the 50 sides of the rim 30, thus permitting the arms 23, to be pressed toward each other and released from the flanges 33, to the end, that the tray 29, may be tilted on the pivots or buttons 27, until the openings 28, in the 55 tray, register with the elongated buttons, so

that they can be disengaged therefrom. Each side of the tray 29, is provided rearwardly of the pivots 27, with a catch 35, to receive a cord 36, the lower end of which may be secured by means of a hook 37, in an opening 38, in the front end of each of the channeled pieces 14, of the seat. The upper portion of the cord 36, may be attached in any suitable manner to any suitable support, such as a coiled spring of the usual kind used for baby jumpers or swings. A cord 39, secured at one of its ends to each of the chains 20, at the upper portion of the back 10, and at its other end to a suitable support or spring (not shown), may also be employed when it is desired to use the holder for the purpose of a swing seat or the seat of a baby jumper, and it is evident that as the catches 35 on the sides of the tray 29, are located in front of the points at which the lower ends of the cords or cables 36 are attached to the seat member 11, said cords or cables and said catches will sustain the holder in substantially a horizontal position; or, in other words, will prevent it tipping forwardly, and thereby allowing the child to slip between the front portion of the seat 11, and the rear portion of the tray, all of which will be clearly understood by reference to Fig. 6 of the drawings.

In Fig. 5^a, I have shown the holder mounted on a sulky or pull-cart, which may be of the ordinary or any preferred construction, and which forms no part of the present invention, but in order to illustrate the adaptability of my improved holder or seat for use in connection with a vehicle, I have deemed it necessary to illustrate one form of such vehicle, in which it will be seen that the rear portion of the frame 40, of the vehicle is provided at each of its rear corners with a forwardly extended projection 41, to engage the rear portion of the seat member 11, while the tongue or handle 42 of the vehicle has pivoted on its upper portion, near the front part of the seat member 11, a catch 43, which can be turned in and out of engagement with the seat member 11, and held in engagement therewith by means of a collar 44, slidably mounted on the tongue or handle 42, so as to engage the lower portion of said catch.

By reference to Fig. 2 of the drawings, it will be seen that the links 19, are pivoted at their outer ends to the sides of the back member 10, at points at greater distances from the pivots 16, than are the pivoted outer ends of the links 18, which construction, I have found by experiment and practice, enables the parts of the holder to be folded into a more compact space than if the pivot points of the outer ends of said links were located at the same distances.

from the pivots 16, which unite the back and seat members.

From the foregoing and by reference to the drawings, it will be readily understood and clearly seen, that when the parts are in the positions shown in Figs. 1, 5^a and 6 of the drawings, the holder is ready for the occupancy of a child, and that the child or baby can be easily placed within the holder by extending his or her legs downwardly between the arms 23 and outwardly between the front portion of the seat member 11, and rear portion of the tray 29, or if desired, the arms 23, may be pressed toward each other, which will release them from the flanges 32, on the lower part of the sides of the tray, when the latter may be turned on its pivots 27, until the elongated portion of the openings 28, in said tray register with the elongated buttons 27, at which time it is obvious that said buttons may be removed from said openings and the tray detached, after which the child may be placed on the seat 11, and the tray attached to the arms by a reverse operation to that just above described.

Having thus fully described my invention, what I claim as new and desire to secure by Letters Patent, is—

30 1. A folding and convertible holder including a back, a seat movably connected thereto, bracing means composed of links pivotally connecting the back and seat, and tray-supporting arms coöperating with the back and bracing means to lock the latter in operative position.

2. A folding and convertible holder including a back, a seat movably connected thereto, bracing members including connected links pivotally secured to both the

back and seat, and tray-supporting arms connected to said bracing members and back and locking the links in extended relation.

3. A folding and convertible holder including a back, a seat movably connected thereto, pivotally connected links arranged intermediate the back and seat, tray supporting arms pivotally connected to one of said links, and means for removably connecting said arms to the back to maintain the links in extended relation.

4. In a folding and convertible holder, pivotally supported arms, a tray, the edges of the tray being formed to provide channels to receive and inclose the forward portions of the arms, and coöperating locking means formed on the tray and arms, the bottom of the channel being interrupted on the inner edges of the channel to permit rotative movement of the tray when the arms register with such interrupted portions.

5. In a folding and convertible holder, pivotally supported arms, a tray, the edges of the tray being formed to provide channels to receive and inclose the forward portions of the arms, and coöperating locking means formed on the tray and arms, the bottom of the channel being interrupted on the inner edges of the channel to permit rotative movement of the tray when the arms register with such interrupted portions, said arms being resilient to normally register with that portion of the channels having a bottom wall.

JOHN H. RUEL.
